(57) **CLAIM**

The ornamental design for earbud cover, as shown and described.

DESCRIPTION

FIG. 1 is a top perspective view of an earbud cover showing my new design;

FIG. 2 is a front elevational view thereof;

FIG. 3 is a rear elevational view thereof;

FIG. 4 is right side elevational view thereof;

FIG. 5 is a left side elevational view thereof;

FIG. 6 is a top plan view thereof;

FIG. 7 is a bottom plan view thereof; and,

FIG. 8 is a perspective environmental view thereof.

The broken lines shown on the drawings are included for the purpose of illustration and form no part of the claimed design.

1 Claim, 4 Drawing Sheets
